UNITED STATES PATENT OFFICE.

KATIE GRATER, OF STERLING, ILLINOIS.

CARPET-BEATING RACK.

1,301,430.

Specification of Letters Patent. Patented Apr. 22, 1919.

Application filed November 22, 1918. Serial No. 263,790.

To all whom it may concern:

Be it known that I, KATIE GRATER, a citizen of the United States, residing at Sterling, in the county of Whiteside and State 5 of Illinois, have invented certain new and useful Improvements in Carpet-Beating Racks, of which the following is a specification.

My invention pertains to carpet cleaning 10 racks, and is intended for the support of carpets, rugs, bedding and other articles, at a convenient height from the ground, when the same are being beaten or aired. It comprises a sectional frame, the parts of which 15 can be disconnected and stowed away in a small space. It can also be reduced in size, so as to be used on the inside of a house, for supporting bedding, curtains and the like.

Another feature of my device consists in 20 the use of resilient supporting means for the articles to be cleaned, so that the dirt can be removed therefrom with greater rapidity. These and other advantages of the invention will be more fully understood from the 25 following specification, reference being had to the drawings accompanying the same, in which:

Figure 1 shows my invention in side elevation. Fig. 2 is a plan view thereof. Fig. 30 3. is a detail, showing the joint between two of the frame sections. Fig. 4 is a cross-section through one of said sections. Fig. 5 is a plan view of a curtain stretching frame which is used in connection with my invention. Fig. 6 is a side view of one of the strips from which said frame is formed. Fig. 7 is an end view of one of the sections 35 20. Fig. 8 shows one of the clips 27, detached.

The main frame is supported by means of 40 legs 1, of suitable height, and sectional side pieces and end pieces detachably connected therewith. The side pieces are formed of sections 2, of approximately three feet in 45 length, having on opposite ends tongues 3 and sockets 4, by means of which such pieces are detachably connected. After the pieces are united they are held in place by means of a plate 5, pivoted at one end to one of the 50 sections 2, and turned into position above the end of the other section. The end pieces are formed in a similar manner of sections 6, united in the same way as the side sections, and provided with locking plates 5 55 above the joints. When two of the sections are to be united the plate 5 is turned to one

side, permitting the engagement of the adjacent tongues and sockets. The plate 5 is then turned into line with said pieces, preventing the separation thereof. To disconnect such sections the operation is reversed. 60

The side pieces are preferably formed of four sections, and the end pieces of three sections, whereby a frame of approximately nine by twelve feet, and corresponding with 65 a conventional size of rugs, is produced.

Each of the sections 2 and 6 is provided with a plate 7, bent outwardly into a flange 8, to which flanges are removably attached 70 wires formed of a number of sections, corresponding in length with that of the sections 2 and 6. The wire sections are provided at opposite ends with hooks and eyes, so that the same may be readily connected, or detached. One of such sections in each 75 wire is furnished with a spring coil 10, having a hook on its end by means of which it can be engaged with one of the plates 7. The opposite end of the wire is engaged with a plate 7 on the opposite side of the frame by 80 means of the hook on the end of the short section thereof. Any number of wires can be employed, and they can be extended lengthwise or transversely of the main 85 frame, or both.

When the wires are in position the rug or other article is placed thereon and beaten in the usual manner. For convenience in handling the rug there is provided at one end of the rack a roller device, consisting 90 of sockets 11 attached to the sides of the posts 1, in which sockets are removably held the shanks 12 of forks 13, in which forks are supported the pins 14 of a roller 15. The roller 15 is also formed in sections, united 95 at their ends by means of ferrules 16 on one end of the section, receiving the end of the adjacent section, and held from casual release by means of a bayonet slot and pin connection, as at 17. As a portion of the rug 100 is beaten it is wound upon the roller 15, and when completely rolled up, can be carried away thereon.

During the beating operation the supporting wires are caused to react by the springs 105 10, striking against the lower side of the rug, and cleaning the same in much less time than if the wires were stationary.

When it is desired to store the device, the legs and sections are all disconnected, as 110 well as the wires, whereupon all of the parts can be stowed in a closet or box in compact

space, not exceeding three feet in length. This is a convenience in bungalows and cottages in which the space is limited. It can be used to a large extent independently of the weather or condition of the ground, and can be set up in the snow in mid-winter, if desired. It can also be used on the flat roof of a building. By removing one section from each side and one from each end, the frame is reduced to a six-by-nine size, and can be used on the outside of the house for small sized rugs, or on the inside of such house to support bedding while being aired, or curtains.

To aid in the use thereof with curtain-stretching devices there is provided a frame formed of sectional plates 20, one end-plate of which has a hook 21, and the opposite end with a hooked spring 22. The plates can thereby be connected with the plates 7 at opposite side of the main frame. The sections are removably united by means of pins 23 engaging bayonet-slots 24 in angle-plates 25 of the sections 20. Small wooden strips 26 are supported on the plates 20, and held in place by spring clips 27. The strips 26 are provided with series of pins 28, to which a lace curtain can be attached in the usual manner. By removing or replacing one of the sections 20 the curtain frame can be reduced or increased in size, so as to use the same with small or large curtains, the main

frame of the device being correspondingly changed.

What I claim and desire to secure, is: 35

1. A device of the class described, comprising a frame, formed of sectional pieces, and a plurality of wires adapted to be removably connected with said frame transversely thereof, and formed of detachable 40 sections of approximately the same length as the frame sections, said device being capable of being reduced to a compact space.

2. A device of the class described, comprising suitable supports, frame sections detachably united, and removably connected with said supports, and sectional supporting devices detachably connected with said frame sections, the lengths of said sections being such that the size of said device can 50 be changed from that suitable for the support of an article of conventional size to that of an article of a differing conventional size.

3. A device of the class described, comprising suitable supports; a frame formed of sectional pieces removably connected with said supports; a plurality of sectional wires removably connected with said frame sections; and a sectional roller rotatably and 60 removably supported at one end of said device.

In testimony whereof I affix my signature.
KATIE GRATER.

Copies of this patent may be obtained for five cents each, by addressing the "Commissioner of Patents, Washington, D. C."
